UNITED STATES PATENT OFFICE.

HERBERT D. SHARP, OF SANDUSKY, OHIO.

TOOL FOR REDRESSING VALVE-SEATS.

1,101,888.

Specification of Letters Patent. Patented June 30, 1914.

Application filed October 2, 1913. Serial No. 793,037.

To all whom it may concern:

Be it known that I, HERBERT D. SHARP, a citizen of the United States, residing at Sandusky, in the county of Erie and State of Ohio, have invented a new and useful Tool for Redressing Valve-Seats, of which the following is a specification.

The present invention appertains to a tool or implement for redressing the valve seats of globe valves, and aims to provide a novel and improved device of that character, which shall be comparatively simple, compact and inexpensive in construction, as well as convenient and efficient in its use.

It is the object of the present invention to provide a suitable cutter for redressing a valve seat, and a stem for the cutter, which is designed to be passed loosely through the bonnet of the globe valve, when the usual valve stem is removed, means being provided for centering the cutter spindle within the bonnet, and for rotatably holding the spindle in position, in order that the valve seat may be cut true.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its referred embodiment in the accompanying drawing, wherein the figure is a sectional view of a globe valve, with the valve proper and its stem removed, and with the improved tool applied to the bonnet, parts of the present tool being shown in full, and parts being shown in section.

In the drawing, an ordinary type of globe valve casing 1 has been disclosed, the same embodying the valve seat 2, and the movable bonnet 3 having a bore 4 for the passage of the valve stem, a gland 5 being seated upon the upper end of the bonnet 3 and having an opening 6 for the valve stem. The present tool or implement embodies a spindle or stem 7 adapted to be passed loosely through the bonnet and gland 5, the spindle or stem 7 being of smaller diameter than the usual valve stem. The spindle or

stem 7 is threaded, as at 8, at its lower end, and a cone or centering member 9 is threaded upon the portion 8 of the spindle, the apex of the cone 9 projecting outwardly or upwardly, and a binding nut 10 being threaded upon the portion 8 of the stem 7 to contact with the base of the cone 9 to lock the cone in position.

The lower end of the spindle 7 is provided with a reduced threaded extension 11, upon which the cutter 12 is adapted to be threaded. This cutter may be of any convenient type, and as illustrated includes a flat face provided with cutter teeth 13, for redressing flat valve seats, and an opposite bevel 14 which is toothed for redressing beveled valve seats, it being understood that the cutter 12 may be reversed for use in redressing either flat or beveled valve seats.

The tool also includes a second cone or centering member 15 adapted to be slidably mounted upon the upper end portion of the spindle 7 and having a set screw 16 for locking it at any adjusted position.

A suitable hand wheel 17 is detachably carried by the upper end of the spindle 7, and it is preferable to provide a collar 18 upon the lower end of the spindle 7 against which the cutter 12 may seat.

In use, to redress the seat of a globe valve, the bonnet is first removed, and the valve stem is withdrawn from the bonnet, as will be readily understood. The hand wheel 17 and the centering cone 15 are then removed from the spindle, and the upper end of the spindle is inserted upwardly through the bonnet 3 and the gland 5, in which event, the centering cone 15 is again slipped over the upper end of the spindle 7 and the hand wheel 17 is again attached to the spindle. The bonnet 3 is then again applied to the valve casing, and the spindle 7 is moved downwardly until the cutter 12 seats upon the valve seat 2. The centering cone 15 is then slid downwardly until its apex fits within the opening 6 of the gland 5, in which event, the bonnet is again removed and the inner cone 9 is adjusted outwardly so as to engage within the lower end of the bore 4 of the bonnet. Then, the cone 15 is slid outwardly slightly, for approximately one-sixteenth of an inch, and is locked in position by means of the set screw 16, the inner cone 9 being correspondingly adjusted outwardly in order to center the spindle 7 within the bonnet and to lock the spindle against lon-

5 longitudinal movement, but permitting the same to rotate freely. After the nut 10 has been tightened against the cone 9, the bonnet is again threaded into engagement with the globe valve casing, and when the bonnet is one-sixteenth of an inch from home, the cutter 12 will be brought against the valve seat 2, permitting the valve seat to be redressed by turning the spindle 7 through the medium of the hand wheel 17. As the valve seat is cut, the bonnet may be threaded inwardly, to work the spindle and cutter inwardly, and by continuing this operation, the valve seat may be cut down to the desired extent. After the valve seat has been properly dressed, the bonnet may be removed, and the present tool removed from the bonnet, which will permit the parts of the valve to be assembled for use.

10 15 20 The present device may be employed in connection with various globe valves and the

like, it being noted that the cutter 12 is reversible to redress either flat or beveled valve seats.

Having thus described the invention, what is claimed as new is:—

In a tool of the character described, a spindle adapted to be inserted loosely through a valve bonnet, a cutter mounted upon the lower end of the spindle, a conical centering member adjustably mounted upon the lower end portion of the spindle, and a conical centering member removably and adjustably mounted upon the upper end portion of the spindle. 35

In testimony that I claim the foregoing as my own, I have hereto affixed my signature in the presence of two witnesses.

HERBERT D. SHARP.
